UNITED STATES PATENT OFFICE.

EDWARD ERICKSON, OF LYNN, MASSACHUSETTS, ASSIGNOR TO VICTOR SHOE MACHINERY COMPANY, OF LYNN, MASSACHUSETTS, A CORPORATION OF MASSACHUSETTS.

NEEDLE AND NEEDLE-GUIDE ACTUATING MECHANISM FOR SEWING-MACHINES.

1,364,260.

Specification of Letters Patent.

Patented Jan. 4, 1921.

Application filed December 4, 1919. Serial No. 343,084.

To all whom it may concern:

Be it known that I, EDWARD ERICKSON, a subject of the Republic of Finland, and a resident of Lynn, in the county of Essex 5 and Commonwealth of Massachusetts, have invented certain new and useful Improvements in Needle and Needle-Guide Actuating Mechanism for Sewing-Machines, of which the following is a specification.

10 This invention relates to needle guide mechanisms for shoe-sewing machines and has for its object the production of means for actuating the needle guide positively by the same instrumentalities which actuate the 15 needle whereby a positive relation is maintained at all times between the movements of said needle and guide.

The invention consists of certain novel features of construction and arrangement 20 of parts which will be understood readily by reference to the description of the drawings and to the claims to be hereinafter given.

For the purpose of illustrating the invention, one preferred form thereof is illustrated in the drawings, this form having been found to give satisfactory and reliable 25 results although it is to be understood that the various instrumentalities of which the 30 invention consists can be variously arranged and organized and the invention is not limited to the precise arrangement and organization of these instrumentalities as herein shown and described, except as required by the scope of the appended claims.

Of the drawings—

Figure 1 represents an elevation of a shoe-sewing machine embodying the principles of the present invention.

40 Fig. 2 represents a vertical section of a portion of said machine, and

Figs. 3 to 5 represent diagrams showing the three consecutive positions assumed by the needle, needle guide, and needle guide 45 actuating mechanism during the operation of the machine.

Similar characters indicate like parts throughout the several figures of the drawings.

50 In the drawings, 10 is the base of the machine adapted to be secured to a column and having end frames 11 provided with bearings for the revolute shaft 12.

This revolute shaft 12 has secured thereto, a cam disk 13.

To one of the side frames 11 is secured a work support 14 which may be of any well-known construction.

One of the side frames 11 has also mounted thereon, a shuttle and means for operating same.

As the shuttle forms no part of the present invention, it is believed that it will be unnecessary to illustrate the same.

One of the side frames 11 is provided with 65 two parallel studs or pins 15 which have mounted thereon, a movable frame 16.

This frame has pivoted to the lower end thereof, at 17, an oscillating lever 18, the lower end of which is provided with a roller 70 19 extending into a cam path in the periphery of the cam disk 13.

This slotted lever 18 is provided with a movable fulcrum 20 which may be adjusted by the hand lever 21, to vary the movement 75 of the frame 16, all as described in the Patent No. 1,133,147 issued March 23, 1915, to Lawrence E. Johnson, and myself and on which the present invention is an improvement.

The frame 16 has a long bearing formed 80 therein in which is mounted a shaft 22 having secured to one end a radial arm 23 and having secured on its opposite end a disk 24 on which is mounted a needle guide 25. 85 This needle guide 25 has an opening therein through which the curved needle 26 is adapted to move.

The needle 26 is mounted upon the support 27 having a segment of a gear 28 90 formed thereon and an awl 29 secured thereto.

The needle support 27 is provided with a tubular sleeve surrounding the shaft 22 in the long bearing in the frame 16 about the axis of which it is adapted to be oscillated by the lever 30 having formed thereon at one end, a gear segment 31 meshing with the gear segment 28.

The teeth of the gear segment 31 are of 100 sufficient length to permit the teeth of the gear segment 28 to remain constantly in mesh during the movement of the frame 16 in either direction.

The lever 30 is pivoted at 32 to an end 105 frame 11 and is provided at its rear end

with a roller 33 in the cam path 34 formed in the cam disk 35 secured to and revoluble with the shaft 12.

During the rotation of the disk 35, the cam path 34 operates upon the roller 33 to give the required movement to the needle segment at the proper time.

The lever 30 is provided with an upwardly extending lateral arm 36 to the upper end of which is pivoted a link 37, the opposite end of which is articulated to a lever 38 having formed on its opposite end a loop spreader 39 secured to an oscillating shaft or pin 40 mounted in the upper end 15 of the movable frame 16.

The forward end of the spreader 39 is curved downwardly as indicated in Fig. 2 of the drawings.

This mechanism provides a simple means 20 for spreading the loop of thread at the proper time for the hook of the shuttle to enter the same all as described in the patent above referred to.

The oscillating shaft or pin 40 is provided 25 with a radial arm 41 to the outer end of which is secured at 42 the curved upper end 43 of a link 44, the lower end of which is pivoted at 45 to the outer end of the radial arm 23 secured to the oscillating shaft 22.

30 It is obvious from an inspection of the drawings, that the needle 26, the guide 25, and loop spreader 39 are all positively actuated by the same cam 35 and maintain the same positions relative to each other 35 throughout the various operations of the machine.

This has been found in practice to be 40 greatly desirable in order that the needle guide may be positively moved into the required position to support the needle when such support is most needed without the use of springs or other instrumentalities.

45 It is evident that springs and similar devices are liable to get out of order and fail to operate thereby leaving the needle unsupported and making it possible for the needle to become broken in the operation of the machine, and this is particularly true in high speed stitchers.

50 By means of the present invention, this objection is entirely overcome.

By making the upper portion of the link 44 curved as at 43, there will be no interference with the oscillating shaft or pin 40 55 by the link 44 during the oscillations of the lateral arm 41.

By extending the lateral arm 42 upwardly from the oscillating shaft or pin 40 and having the lateral arm 23 extending rearwardly 60 from the oscillating shaft 22, a peculiar movement is imparted to the needle guide during the operation of the needle 26.

The highest position of the needle 26 is indicated in Fig. 1 of the drawings and the

lowest position of said needle is indicated in 65 Fig. 2 of the drawings.

In the diagrams Figs. 3 to 5 inclusive, several intermediate positions of the needle and needle guide are indicated.

When the needle is in its lowest position, 70 the pivot 42 will be in the position indicated at *a* in Fig. 3 of the drawings.

When said pivot is moved into the position indicated at *b* in Fig. 3, the needle 26 will be raised slightly without raising the 75 needle guide to any appreciable extent.

In other words, at this time the needle is drawing the thread through the work and requires to be supported at a point adjacent to the work and this result is accomplished 80 by the mechanism herein provided.

When the pivot member 42 is moved to the position *c* in Fig. 4 of the drawings, the needle moves up and the needle guide moves upwardly at considerably less speed than the 85 speed of movement of the needle. For instance, the pivot member 42 in moving through an angle of 20° only moves the pivot member 45 through an angle of 7½°.

When the pivot 42 reaches the position *d* 90 in Fig. 5 of the drawings, the needle moves still farther up and the needle guide moves in the same direction at a slower speed.

The pivot member 42 in passing through an angle of 17½° only imparts a movement 95 to the pivot member 45 through an angle of 10½°.

Continued movement of the pivot member 42 in the direction of the arrow *e* on Fig. 5 of the drawings will cause the needle 26 100 and needle guide 25 to move upwardly into the position indicated in Fig. 1 of the drawings with the needle moving a little faster than the needle guide so that when the needle reaches its uppermost position the needle 105 guide is positioned near the barb thereof.

By means of this construction the needle and the needle guide are positively driven by means of the same cam-controlled lever and the needle guide is moved at a speed varying 110 with the speed of the needle whereby the needle guide at all times maintains a position relative to the needle which is most advantageous for the proper operation of the machine.

In the high speed stitcher, the rate of speed is so great that the leather is liable to burn slightly where the awl punctures it and the needle is liable to become coated with burnt leather and stick.

This would cause the breaking of the needle and injury to the work as the needle would not be supported when it was piercing the leather.

By providing positive means for actuating 125 the needle guide this objection is wholly obviated.

It is believed that the operation and its

many advantages will be fully understood without further description.

Having thus described my invention, I claim—

- 5 1. In a shoe-sewing machine, the combination of a needle; a needle guide; and a single means for actuating said needle and guide positively and continuously at varying speeds.
- 10 2. In a shoe-sewing machine, the combination of a needle; operating mechanism therefor including a cam-controlled lever; a needle guide; and means actuated by said lever for imparting a positive and continuous movement to said needle guide at varying speeds.
- 15 3. In a shoe-sewing machine, the combination of a needle; operating mechanism therefor including a cam-controlled lever; a needle guide; a pivot therefor; an actuating arm on said pivot; an oscillating shaft; a lever on said shaft connected to said cam-controlled lever; a radial arm on said oscillating shaft; and a link connecting said radial arm and said actuating arm.
- 20 4. In a shoe-sewing machine, the combination of a needle; operating mechanism therefor including a cam-controlled lever; a needle guide; a pivot therefor; a rearwardly extending actuating arm on said pivot; an oscillating shaft; an upwardly extending lever on said shaft connected to said cam-controlled lever; an upwardly extending radial arm on said oscillating shaft;
- 25 5. In a shoe-sewing machine, the combination of a needle; a carrier therefor; a needle guide; a cam-controlled lever; and means operable by said lever for actuating said needle carrier and the guide therefor positively and continuously at varying speeds.
- 30 6. In a shoe-sewing machine, the combination of a needle; a carrier therefor having a segment of a pinion formed thereon; a needle guide; a cam-controlled lever provided with a gear segment meshing with said pinion segment and having a lateral arm; an oscillating pivot pin; a lever thereon; a link between said lever and lateral arm; a radial arm on said pivot pin; and means pivoted to said radial arm for positively actuating said needle guide.
- 35 7. In a shoe-sewing machine, the combina-

tion of a needle; operating mechanism therefor including a cam-controlled lever; a loop-spreader comprising a tapered finger operating in a plane parallel to the needle; a needle guide; and means operable by said cam-controlled lever for simultaneously moving said loop-spreader and needle guide positively and at varying speeds.

8. In a shoe-sewing machine, the combination of a needle; operating mechanism therefor including a cam-controlled lever; a loop-spreader comprising a tapered finger operating in a plane parallel to the needle; a needle guide; an oscillating pivot member for said loop-spreader; an arm secured to said pivot member; an actuating arm for said needle guide; a link connecting said arms; and means operable by said cam-controlled lever for simultaneously moving said loop-spreader and needle guide.

9. In a shoe-sewing machine, the combination of a needle; operating mechanism therefor including a cam-controlled lever; a loop-spreader comprising a tapered finger operating in a plane parallel to the needle; a needle guide; an oscillating pivot member for said loop-spreader; an arm secured to said pivot member; an actuating arm for said needle guide; a link connecting said arms curved at its upper end to clear said pivot member; and means operable by said cam-controlled lever for simultaneously moving said loop-spreader and needle guide.

10. In a shoe-sewing machine, the combination of a needle; operating mechanism therefor including a cam-controlled lever; a loop-spreader comprising a tapered finger operating in a plane parallel to the needle; a needle guide; an oscillating pivot member for said loop-spreader; an upwardly extending arm secured to said pivot member; an actuating arm for said needle guide extending rearwardly from the pivot thereof; a link connecting said arms; and means operable by said cam-controlled lever for simultaneously moving said loop-spreader and needle guide.

Signed by me at 746-7 Old South Bldg., Boston, Mass., this 29th day of November, 1919.

EDWARD ERICKSON.
